(57) **CLAIM**

I claim the ornamental design for an weightlifting footrest, as shown and described herein.

DESCRIPTION

FIG. 1. Is a front perspective view of my weightlifting footrest with the dotted lines showing being for illustrative purposes only and to which no claim is made;

FIG. 2. Is a right side elevational view thereof with the left side elevational view being a mirror image thereof and with the dotted lines showing being for illustrative purposes only and to which no claim is made;

FIG. 3. Is a back view thereof;

FIG. 4. Is a front view thereof;

FIG. 5. Is a top view thereof; and,

FIG. 6. Is a bottom view thereof.
